(57) **CLAIM**

The ornamental design for a loading ledge device with friction surface, as shown and described.

DESCRIPTION

FIG. 1 is a front perspective view from above of a loading ledge device with friction surface showing our new design;
FIG. 2 is a rear perspective view from below thereof;
FIG. 3 is a bottom plan view thereof;
FIG. 4 is top plan view thereof;
FIG. 5 is a rear elevational view thereof;
FIG. 6 is a front elevational view thereof;
FIG. 7 is an end view thereof; and,
FIG. 8 is the other end view thereof.
